UNITED STATES PATENT OFFICE.

JOSEPH B. RIDGWAY, OF CURTIS, NEBRASKA.

ATTACHMENT FOR DISK HARROWS.

1,051,824.

Specification of Letters Patent. Patented Jan. 28, 1913.

Application filed June 12, 1912. Serial No. 703,275.

To all whom it may concern:

Be it known that I, JOSEPH B. RIDGWAY, a citizen of the United States, residing at Curtis, in the county of Frontier and State of Nebraska, have invented new and useful Improvements in Attachments for Disk Harrows, of which the following is a specification.

This invention relates to an improved attachment for disk harrows having for its object to convert an ordinary disk harrow into a useful and efficient land roller.

A further object of the invention is to produce simple and inexpensive devices capable of being mounted on the individual harrow disks for the purpose of converting the same into individual rollers and pulverizers.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing, Figure 1 is a view in side elevation of a harrow disk equipped with the improved attachment, parts having been broken away for the purpose of showing the construction more clearly. Fig. 2 is a sectional view taken on the line 2—2 in Fig. 1. Fig. 3 is a sectional view taken on the line 3—3 in Fig. 1. Fig. 4 is a perspective detail view of one of the members or units of the improved attachment removed from the disk.

Corresponding parts in the several figures are denoted by like characters of reference.

The improved attachment is composed of two similar members or units 1, 1 which are adapted to be mounted on an ordinary harrow disk 2 and which combine to form a hoop or tire surrounding said disk and co-acting therewith to constitute a roller and pulverizer.

The units of the improved attachment may be conveniently made by pressing or stamping of suitable sheet metal, and each

unit includes two outwardly divergent side walls 3, 3, arcuate ground engaging tread plates 4, 4 extending from the outer edges of said side walls and converging at the apex 5, and disk engaging face plates 6, 6 which extend inwardly from the inner edges of the divergent side walls intermediate said side walls, said face plates being suitably shaped to engage the two sides or faces of the disk 2, one of said faces being convex and the other concave.

The meeting ends of the units, when applied to a disk, will overlap, as shown at 7, and they may then be secured in position by means of a connecting bolt 8 extending through the overlapping portions, said bolt being curved, as shown, and the curved portion thereof engaging the edge of the disk 2. Additional similarly curved bolts 8 may be used at intervals to connect the side walls of each unit for the purpose of preventing radial movement of said units with reference to the disk.

For convenience in construction, each unit may be made of two separate plates connected together at the apex 5 of the tread plates by means of rivets 9 or in any other suitable and convenient manner.

As will be seen from the foregoing description, taken in connection with the drawing hereto annexed, a simple and efficient attachment has been provided which may be readily applied to the disks of an ordinary disk harrow which will thus be converted into a land roller and clod pulverizer. The face plates 6 which engage the opposite sides or faces of the disk will serve to maintain the units of the device firmly and securely in proper position for operation in connection with the bolts 8, which when tightened will cause the disk to be clamped between the face plates 6, 6.

Having thus described the invention, what is claimed as new, is:

1. A device of the class described comprising two semi-circular units combining to form a disk engaging tire, each unit having outwardly divergent side walls, inwardly converging tread plates, and face plates extending inwardly from the inner edges of the side walls intermediate said side walls.

2. A device of the class described comprising two semi-circular units having overlapping meeting ends, each unit having outwardly divergent side walls, inwardly converging tread plates extending from the

outer edges of said side walls, and face plates extending inwardly from the inner edges of the side walls intermediate said side walls.

5 3. A device of the character described comprising two semi-circular units, each including outwardly divergent side walls, a tread portion connecting the outer edges of the side walls, face plates extending inwardly from the inner edges of the side walls intermediate said side walls, and clamping bolts extending through the side walls.

4. A device of the character described comprising two semi-circular units, each including outwardly divergent side walls, arcuate tread plates extending from the outer edges of the side walls and connected together, face plates extending inwardly from the inner edges of the side walls intermediate said side walls, and clamping bolts extending through the side walls.

5. The combination with a disk, of an attachment comprising two semi-circular units, each including outwardly divergent side walls, a tread portion connecting the

outer edges of the side walls, face plates extending inwardly from the inner edges of the side walls, and curved clamping bolts extending through the side walls and engaging the edge of the disk to prevent radial movement of the units. 30

6. The combination with a disk, of an attachment comprising two semi-circular units having overlapping meeting ends and 35 each including outwardly divergent side walls, a tread portion connecting the outer edges of the side walls, and face plates extending inwardly from the inner edges of and between the side walls; and clamping bolts extending through the side walls at the overlapping portions thereof and at intermediate points, said clamping bolts having curved portions engaging the edge 40 of the disk. 45

In testimony whereof I affix my signature in presence of two witnesses.

JOSEPH B. RIDGWAY.
